HUMBERT A. GALASSO, OF BROOKLYN, NEW YORK, ASSIGNOR TO WILLIAM H. EDWARDS, OF BROOKLYN, NEW YORK

DENTAL IMPRESSION BITE

Application filed July 20, 1928. Serial No. 294,162.

This invention relates to devices intended to be used by dentists to obtain an impression of the gums or of the outermost extremities of the teeth of a patient so that when the 5 artificial teeth made in accordance with the impression are inserted into the mouth of the patient, proper and accurate occlusion is obtained.

Difficulty has heretofore been experienced 10 in practicing the methods heretofore customarily used in aligning artificial teeth to occlude accurately, for the reason that the wax impression formerly made to determine the "bite" or occlusion of the teeth has necessarily been inaccurate, due to unavoidable 15 deformation of the wax impression. The customary practice has been to make a plaster impression, of the teeth and gums at the places where artificial teeth are to be inserted, and then in addition, to make a wax impression of the teeth to be bridged to determine the "bite". To strengthen the impression or mold in so far as possible, a comparatively thick piece of wax has heretofore 20 been used to obtain the impression of the "bite". Such a thick wax member is so squeezed by the teeth of the patient that the wax is forced about the upright faces of the teeth, and an impression taken of practically 25 the entire tooth. Where the teeth are irregular, and the surfaces inclined in certain directions, a true impression of the bite is not retained for the reason that the soft wax member, when removed from the teeth is de- 30 formed by the irregular surfaces of the teeth, especially if the teeth are "undercut". Furthermore, the wax impression member in such cases is often so held by the teeth that it cannot be removed without injuring the im- 35 pressions and when forced off the teeth, stresses are put on the member which distorts the impression. A further disadvantage is that the wax must be comparatively soft to give a proper impression, whereby the hand- 40 ling in the various operations necessary in making the artificial teeth, distorts the wax impression member and results in artificial teeth which do not properly occlude.

Mechanical dentists, therefore, to avoid 45 these difficulties in so far as possible, must

cut away much of the wax impression of the tooth so as to leave the impression in the wax of only the extreme outer portion of the teeth. Even by so cutting away the wax impression member, distortion of said member may occur in handling and cutting with the consequent disadvantages above mentioned. 55

My invention contemplates the provision of a wax impression member so designed as to give the impression of the "bite" of the patient only. The greater part of said member is made of comparatively hard material and is suitably reinforced, to avoid the danger of deformation thereof during the process of making and articulating the teeth. 60 The various objects of my invention will be clear from the description which follows and from the drawings, in which,

Fig. 1 is a top plan view of my improved impression member designed for use where there are some teeth in the patient's mouth. 70

Fig. 2 is a front view of the same.

Fig. 3 is a vertical section of the same.

Fig. 4 is a perspective view of the same as it appears after the impression or "bite" of a 75 patient's teeth has been taken.

Fig. 5 is a view similar to Fig. 1 of a modified form of my invention, adapted to be used where there are no teeth in either or both jaws of the patient. 80

Fig. 6 is a vertical section of the same,

Fig. 7 is a perspective view, partly in section, of part of a patient's mouth showing how my improved impression member may be used, and Fig. 8 is a similar view of a modified form of said member. 85

In that practical embodiment of my invention which I have illustrated, I prefer to use an impression member which is made up partly of hard and comparatively unimpressionable wax, and partly of soft wax adapted to take the impression. 90

Where the upper and lower jaws of the patient both contain some teeth, I prefer to use that form of my invention illustrated in 95 Figs. 1 to 4 inclusive, though it will be understood that the length and curvature of the member there illustrated may be greatly varied, depending upon the number of teeth and the spacing of the teeth in the mouth of the 100

patient. In this form, I prefer to provide two layers 10 and 11 of comparatively soft wax, arranged on the outer faces of the member and exposed thereon. Said layers are separated by the layer 12 of comparatively hard wax, a depression as 13 being preferably formed on each face of the hard wax layer for the reception of the layers 10 and 11. Said layer 12 of hard wax will therefore be comparatively thick at the edges and thin at the remainder thereof, whereby the entire member is braced and made resistant to deformation under a comparatively wide stretch of temperatures and under the stresses due to handling.

The member is used by placing it between the two jaws of the patient, for him to bite upon until the teeth come together as far as they can. It will be understood that the wax may be somewhat heated in the customary manner before insertion in the patient's mouth so that no difficulty will be experienced in biting through the soft layers 10 and 11. As the hard layer 12 is reached, however, a greater resistance is offered to the "bite" of the patient but said layer 12 being comparatively thin, those teeth of the patient which would naturally meet in the mouth cut through said layer 12 a sufficient distance to show precisely how the teeth are spaced vertically and horizontally, thereby enabling the dentist to determine the proper occlusion with accuracy and precision.

It will be further understood that while the layer 12 is resistant to deformation, the "bite" of the patient puts such stress upon the member as to cause said member to be deformed to correspond with the teeth of the patient. Before the removal of the impression member from the mouth, cold water is poured on the member to set the softened wax, the layers of wax and particularly, the layer 12 then becoming sufficiently hard to prevent deformation under ordinary handling and temperatures.

The usual plaster impression having been taken of the mouth, the dentist may use my improved impression member to determine the proper occlusion of the teeth. Since impressions only of the outermost extremities of the teeth are taken, there is no material to interfere with the fitting of my improved member upon the plaster cast of the teeth of the jaw to be supplied with artificial teeth. Said member may therefore be fitted upon the plaster cast and a suitable cast made of the outermost portions of the teeth in the opposing jaw by pouring plaster into the cavities on the opposite side of the wax impression member. Said member may then be cut or molten away and the plaster cast set in an articulator so that the positions and heights of the needed teeth and the occlusion thereof may be accurately determined. It will be seen that all of the variations of

the extremities of the teeth are faithfully molded into the impression member, particularly when it is heated and because of its comparatively thin structure. No deformation due to the obstruction offered by "undercut" or irregular teeth occurs, when the member is removed from the mouth of the patient, such as would ordinarily occur if the present type of comparatively thick impression member were used. It will also be seen that due to the layer 12 of comparatively hard wax, no deformation of the member occurs under the stress put upon the member to lift it from the mouth, since the soft layers 10 and 11 are sufficiently braced by said comparatively hard layer.

If desired, one or both of the layers 10 and 11 may be coated with a sheet of tin foil 14 so as to protect the soft layers during the packing and shipping of the members. Said tin foil may also be used to carry indicia such as printing and instructions, if desired.

Referring now to Figs. 5, 6 and 8, I have there shown a comparatively thick member 15 of about the height desired for the artificial teeth, and composed substantially throughout of hard wax with preferably a single layer of soft wax as 16 thereon. If desired, said member 15 may be additionally braced and supported against deformation as by means of the wire 17 imbedded therein. This form of my invention is intended to be used where there are no teeth at all in either or both jaws. In that case, the member 15 is arranged with the layer 16 of soft wax adjacent the gum and the impression or "bite" of the gum is made. Where there are no teeth in both jaws, two of such members 15 are placed together with the surfaces 18 thereof in contact so that impressions of both gums may be taken simultaneously. It will be understood that if there are no teeth in one jaw and some teeth in the other, the member 15 is used in connection with the member shown in Figs. 1 to 4 inclusive. It will also be understood that the member 15 may be supplied to dentists so that the dentist may spread a layer of soft wax on the face 18 to obtain the "bite" where there are some teeth in one jaw. It will further be understood that the surfaces 18 of the members 15 being of hard wax, may easily be trimmed with a knife so that said surfaces may properly meet in the mouth of the patient throughout the whole length thereof, where two such members are used. If only one member 15 is used, then the surface 18 of the member 15 may be trimmed to properly meet the teeth of the patient remaining in the other jaw.

Referring to Fig. 8, I have shown a concave layer 19 of soft wax disposed outside of the hard wax. By making the soft wax layer concave, it becomes possible to obtain the "bite" of the gums of the patient with much greater accuracy. The extremities of the

gums seldom lie in a plane and for that reason, that member 15 which has a comparatively flat wax layer might not contact with certain parts of the gums. By concaving the layer 19 as shown, however, this difficulty is avoided so that contact is made throughout the entire extremities of the gums and a good "bite" obtained.

It will be seen that I have provided an improved wax impression member sufficiently resistant to deformation before and after impressions have been made therein to meet the severe requirements of practical use; that my improved member, being so designed as not 10 to take in the impressions of the undercuts or inclined surfaces of the teeth, cannot be deformed when removed from the mouth and that said member is further designed so that the precise occlusion of the teeth may be 15 20 easily and accurately determined.

While I have shown and described the preferred embodiments of my invention, it will be understood that various changes may be made therein without departing from the 25 spirit and scope of this invention so that I do not wish to be understood as limiting myself to the precise structure herein shown and described, but intend to claim my invention as broadly as may be permitted by the state 30 of the prior art and the terms of the appended claims.

I claim:

1. In an article of manufacture for use at room temperatures without heating as an impression member for taking the full bite of an upper or lower jaw in which there are no teeth, a thin and comparatively wide outer layer of soft wax, soft enough at room temperatures to take impressions of the extreme 40 end only of the gum of a patient, a hard wax supporting member having a groove on one surface thereof in which said thin layer of soft wax is maintained, said member being performed into approximately U-shape 45 and substantially square in cross-section, the surface of said member opposite the soft wax layer being adapted to be trimmed to height to engage the corresponding surface of a similar member or the teeth of the other jaw 50 of the patient, and the front and back of said member being adapted to be trimmed to the lip and face line.

2. In an article of manufacture for use in taking the full bite of an upper or lower jaw 55 in which there are no teeth, without change in the shape thereof except trimming as herein-after mentioned, a comparatively hard wax supporting member having a depression in one face thereof and substantially flat on the 60 opposite face thereof, and having substantially parallel front and back cylindrical walls, said faces being spaced apart a distance substantially equal to tooth height and the front and back walls being substantially 65 parallel and similarly spaced, said flat sur-

face, front and back walls being adapted to be trimmed to engage the ends of the teeth of the other jaw of the patient or the corresponding surface of a similar member, and a thin layer of comparatively soft wax in said 70 depression.

3. In an article of manufacture for use at room temperatures as an impression member for taking the full bite of an upper or lower jaw, a thin and comparatively wide outer layer of soft wax adapted to engage the gum of one jaw of a patient to receive impressions of the outermost extremities of said gum only, and a substantially U-shaped hard wax supporting member preformed to its final shape and having a depression on one face thereof for the reception of said layer of soft wax and of substantially tooth height, said supporting member being sufficiently soft to be trimmed to space the surface opposite the depression from the gum of the other jaw at tooth height therefrom and substantially parallel thereto.

4. In an article of manufacture for use at room temperatures without heating as an impression member, to take the full continuous bite of an upper or lower jaw in which there are no teeth, a hard wax annular body member preshaped to approximately fit the alveolar ridge, said member being of substantially tooth height and having a substantially flat surface on one face thereof and a depression on the opposite face thereof and substantially parallel, cylindrical front and back walls, and being adapted to be trimmed on said walls and said flat surface to extend to a height not greater than that sufficient to meet the teeth in the other jaw where there are teeth or to meet a corresponding face of a similar member inserted in the other jaw, and a thin and comparatively wide layer of soft wax maintained in said depression, said soft wax being softer than that of said member and soft enough to take impressions at room temperatures.
